CARBURETOR DE-ICER

Maurice A. Gehner, St. Louis, Mo., assignor to Carter Carburetor Corporation, St. Louis, Mo., a corporation of Delaware

Application January 29, 1952, Serial No. 268,795

6 Claims. (Cl. 261—41)

This invention relates to carburetors for internal combustion engines, particularly of the automotive type and consists in novel means for dislodging ice formations in the vicinity of the idle port and throttle valve.

The fuel and air which emerge from the idle port in a carburetor, and which pass the partially closed throttle valve, in expanding upon entry into the portion of the carburetor mixture conduit and intake manifold posterior to the carburetor throttle, cause a substantial reduction in temperature. This cooling action, under certain atmospheric conditions, say, when there is a relatively high degree of humidity and the temperature is near freezing, results in ice formation which frequently obstructs the idle port and mixture conduit. Such ice, forming in and around the idle port, may cause a particularly annoying stalling of the engine when the throttle valve is returned to idling position and may greatly impede restarting of the engine.

The present invention has for its principal object to provide means for avoiding or dislodging such ice formations. The means herein illustrated for accomplishing this purpose consists in a small spring wire which projects through the idle port and into the path of the throttle valve so as to be shifted by the throttle valve, each time it is returned to idle position, for dislodging any ambient ice.

In the accompanying drawing which illustrates the invention:

Fig. 1 is a vertical transverse section of a carburetor embodying the invention.

Fig. 2 is a similar view showing the lower portion only of the carburetor, but with the throttle valve in slightly open position.

The carburetor illustrated has a downdraft mixture conduit 5 with an air inlet horn 6 at the upper end in which is mounted a pivoted butterfly choke valve 7 controlled by any suitable manual or automatic mechanism. In the lower part of the mixture conduit there is a butterfly throttle valve 8, which is manually controlled by the usual lever and linkage parts (not shown), and the lower extremity of the carburetor barrel is provided with a flange 9 for attachment to the engine intake manifold.

Adjacent the mixture conduit there is a constant level chamber 10 enclosing the usual level controlling float 11. In the lower part of the constant level chamber is a main metering orifice element 12 through which fuel is supplied to upwardly inclined, main fuel passage 13 opening through a nozzle 14 into primary venturi tube 15. Idling fuel is supplied through a metering tube 16 communicating with the main fuel passage, posterior to orifice element 12, and idling passages 17 and 18 opening through ports 19 and 20 adjacent and posterior to the edge of throttle valve 8 when closed. An idling mixture adjusting screw 21 cooperates with lowermost port 20.

A cross passage 22 is provided in the wall of the mix-

2

ture conduit to facilitate punching or drilling of idle port 19. This passage is closed at its outer end by a plug 23. A small piece of resilient wire 24 projects inwardly from plug 23 through port 19 and into the path of the left-hand wing of throttle valve 8 so as to be shifted thereby, as the throttle valve approaches its closed position, to dislodge any ice which may be formed in or about the port. Of course, port 19 will be constructed to supply the proper quantity of idling fuel notwithstanding the slight space occupied by wire 24.

As the throttle valve is opened, as in Fig. 2, wire 24 returns to its original configuration by its own resiliency and again sweeps port 19, an advantage, since ice may form or re-form about the port during idling operation, due to clearance provided between the edge of the throttle disk and the mixture conduit wall for the supply of air to the engine even at normal idle position of the throttle.

A spring strip or other shiftable element may be substituted for the wire 24 and the manner of mounting thereof may be varied, as well as the shape and extent of the element.

The invention may be modified in these and other respects as will occur to those skilled in the art, and the exclusive use of all modifications as come within the scope of the appended claims is contemplated.

I claim:

1. The combination in a carburetor having an idle port and a throttle valve adjacent said port of a movable element extending into said port and into the path of said throttle so as to be shifted by said throttle, during its movement, to avoid ice blocking of said port.

2. The combination in a carburetor having an idle port and a throttle valve adjacent said port of a movable element extending into the path of said throttle and engagable thereby so as to be shifted by said throttle, during movement thereof, to dislodge ice formations.

3. In a carburetor, a mixture conduit, a throttle valve therein, an idle port in the wall of said conduit adjacent said valve, and an element shiftable adjacent said port, during movement of said valve, to dislodge ambient ice.

4. In a carburetor, a mixture conduit, a throttle valve therein, an idle port in the wall of said conduit adjacent said valve, and an elongated, resilient element projecting into said port and into the path of said valve so as to be shifted thereby during valve movement, to dislodge ambient ice.

5. In a carburetor, a mixture conduit, a throttle valve therein, an idle port in the wall of said conduit adjacent said valve, a plug in the wall of said conduit adjacent said port, and a spring wire projecting from said plug into said port and into the path of said valve so as to be shiftable thereby during at least a portion of the movement of said valve to dislodge ice in and near said port.

6. The combination as described in claim 5 in which said spring wire is located on the side of said valve which approaches said port when said valve is closed so that the ice dislodging shifting of said wire occurs as said valve reaches closed position.
